UNITED STATES PATENT OFFICE.

IDA A. DIRK, OF CHICAGO, ILLINOIS.

DESIGN FOR A DOLL.

Application filed June 30, 1928. Serial No. 27,341. Term of patent 3½ years.

To all whom it may concern:

Be it known that I, Ida A. Dirk, a citizen of the United States of America, and a resident of Chicago, county of Cook, and State of Illinois, have invented a new, original, and ornamental Design for a Doll, of which the following is a specification, reference being had to the accompanying drawing, forming part thereof.

I claim:—

The ornamental design for a doll, as shown.

IDA A. DIRK.
